UNITED STATES PATENT OFFICE.

WILLIAM EDWIN PEMBLETON, OF WITTENBERG, WISCONSIN.

TELEPHONE-CIRCUIT.

SPECIFICATION forming part of Letters Patent No. 678,304, dated July 9, 1901.

Application filed June 27, 1900. Serial No. 21,770. (No model.)

To all whom it may concern:

Be it known that I, WILLIAM EDWIN PEMBLETON, a citizen of the United States, and a resident of Wittenberg, in the county of Shawano and State of Wisconsin, have invented 5 a new and Improved Telephone-Circuit, of which the following is a full, clear, and exact description.

This invention relates to improvements in 10 telephone-circuits; and the object is to so arrange the circuit as to enable subscribers to know whether the operator's set at central is cut in or out while conversation between two subscribers is being carried on, and, further, 15 to make it impossible for a third party to be connected by the operator carelessly or otherwise with the two talking subscribers.

I will describe a telephone-circuit embodying 20 my invention and then point out the novel features in the appended claims.

Reference is to be had to the accompanying drawings, forming a part of this specification, in which similar characters of reference indicate corresponding parts in both the figures.

25 Figure 1 is a diagrammatic view of a telephone-circuit embodying my invention, and Fig. 2 is a partial elevation and partial section of a switch mechanism employed.

Referring to the drawings, 1 designates a 30 switchboard arranged at central, upon which double switches are arranged. I have here shown double spring-switches 2 and 3, the spring-switch 2 being adapted for engagement with either one of the switch-points 4, 5, 35 while the spring-switch 3 is adapted for engagement with either one of the switch-points 6, 7, and attached to the spring-switches are the jack-plugs 8, 9, 10, and 11.

For illustration I have shown two subscribers' lines A and B. The plug 8 may 40 serve to close the line A in the jack 12, and the plug 9 may serve to close the line B in the jack 13. Arranged in the central office are spring switch-points 14, 15, 16, 17, 18, 19, 45 20, 21, 22, 23, 24, 25, 26, 27, 28, and 29. These several switch-points are arranged in pairs, the several pairs forming a set. Another set comprises spring switch-points 30, 31, 32, 33, 34, 35, 36, 37, 38, 39, 40, 41, 42, 43, 44, and 45. 50 The end contact-plates of each set are curved in such manner as to form a locking device

for a circuit-closer, as will be hereinafter described.

The circuit-closers of the sets consist of swinging levers 46 and 46^a, each carrying at 55 one end oppositely-extended arms 47 and 48 and 47^a and 48^a, of insulating material, and on these extended arms are metal sleeves 49 and 50 and 49^a and 50^a, designed to close the circuit through pairs of contact-plates, as will 60 be hereinafter described.

The operator's set comprises a transmitter 51 and a receiver 52, and also arranged in the operator's set is an extra large transmitter 53, in front of which alarm-sounding devices, such as bells 54 and 55, are placed. 65 These alarm devices are designed to be sounded one after the other, and they are of different pitch, so that by their succession of sounding a subscriber may know the position of 70 the switch mechanism in the operator's set.

In operation, assuming that the subscriber A wishes to call subscriber B, A rings up central, and the operator inserts the plug 8 into the jack 12, the plug 8 being connected with 75 the plate 2, from which a wire 56 extends, and has connections with the spring-contacts 18, 22, and 26. The circuit-closing sleeves 49 and 50 are normally held in engagement with the contact-springs 14 and 15 and 16 and 17 by 80 the locking connection of said spring-plates. As the lever 46 is moved to force the circuit-closer forward the sleeve 49 closes the circuit through the contact-springs 18 and 19, while the sleeve 50 closes the circuit between the 85 contact-springs 20 and 21. As the movement is continued these spring-contacts are released, as they engage but slightly with the circuit-closers, and then the sleeve 49 closes the circuit between the contact-springs 22 and 90 23 and the sleeve 50 closes the circuit between the contact-springs 24 and 25, the connections being made simultaneously. Upon a still further movement of the lever 46 these last-named connections are broken and 95 connections are made between the contact-springs 26 and 27 by the sleeve 49 and the circuit is closed between the contact-springs 28 and 29 by the sleeve 50, and as these last-named contacts are made to lock into engagement with 100 the circuit-closers the said circuit-closers will be held in this position until pressure is

brought to bear to remove them upon backward movement. Now when the circuit is closed through the contact-springs 18 and 19 they connect the line 56 and the line 57, which 5 passes through the receiver 52, and thence through the secondary 58 of the induction-coil to the ground. As the plug A is at this time connected to the jack 12 by closing contact-springs 18 19, they connect operator's secondary circuit with subscriber A at the instant the bell 54 is sounded. At this time the contact-springs 20 and 21 are connected, and they close the circuit through the line 59, bell 54, transmitter 53, and line 60, through the 10 battery 61, and the primary 62, to the bell 54, causing said bell to sound, said sound being conveyed through the transmitter 53, through the secondary circuit 58, the wires 57 and 56, to the subscriber A, through the plug 8 and jack 12. It will be seen then that by closing 15 springs 20 and 21 they cause bell 54 to sound, said sound being conveyed to subscriber A in the manner just described, thus informing A that the operator at central is in the act of 20 connecting his set with A's line. When the contact-springs 22 and 23 are connected, it again closes the circuit through the wires 57 and 56 to the subscriber A, and the contact-springs 24 and 25 being connected closes the 25 circuit through the bell 55, the transmitter 53, the primary 62, line 60, to spring 25 and through the bell 55 and wire 63 to the spring-contact 24. This sounds the bell 55, the sound being conveyed through the transmitter 53 to 30 the subscriber A through the wires 57 and 56, &c., as before described. By connecting springs 22 and 23 we can connect operator's secondary circuit with A's line at the instant that the bell 55 is caused to be sounded by 35 closing springs 24 and 25, the sound being conveyed to subscriber A, informing him that the operator's set is now connected with his line. When the circuit - closer 46^a is used, the 40 sleeve 49 must connect the contact-springs 14 and 15 and the sleeve 50 connects the contact-springs 16 and 17. The circuits are then as follows: The object of the connection by springs 14 and 15 through sleeve 49 is to render it impossible for the operator to again cut 45 out signals and still remain connected with the subscriber's line. The sleeves 49^a and 50^a, which had connected the contact-springs 30 31 and 32 33, respectively, when moved close the secondary circuit 65 through springs 50 34 35, line 66, springs 17 and 16, line 67, to the wire 57 and thence through the receiver 52 and induction-coil 58 to the earth. The contact-springs 36 and 37 being closed makes the circuit through the wire 67, wire 59, bell 54, transmitter 53, coil 62, and lines 60 and 65 68, causing said bell 54 to sound and give the alarm, as before described. Contact-springs 30, 31, 32, and 33 will be used only in case a third circuit-closer is used with another set of connecting-cords, 30 and 31 being similar and for the same purpose as for 14 and 15—that is, to prevent the operator from using

46^a to connect his set to the subscriber's line while using a third contact-closer to again properly cut out signals in the same manner 70 as described in connection with the parts 14 and 15. When the contact-springs 38 and 39 are closed simultaneously with the closing of the contact-springs 40 and 41, the circuit is closed through the wires 65 and the contact-springs 38 and 39, line 66, and springs 17 and 16, the lines 67 and 57, through the secondary 58, to the earth. At the same time the circuit of the bell 55 is closed through the wires 63 69, the bell 55, transmitter 53, primary 62, wire 60, wire 70, springs 14 and 15, and line 71 to contact 41. Contact-springs 38 and 39 being closed connect operator's set with subscriber's line at the instant that the bell 55 is sounded by closing springs 40 and 41, thus informing the operator that the operator's set is fully connected with the subscriber's line. The contact-springs 42 and 43 being connected makes the operator's secondary circuit for the circuit - closer 46^a 90 through wire 65, contact-springs 42 and 43, wire 66, contact-springs 17 and 16, wire 67, wire 57, through the receiver 52, and thence through the secondary 58 to the ground. The contact-springs 44 and 45 being closed makes 95 the operator's primary circuit for the circuit-closer 46^a as follows: from the contact-spring 45, through the wire 64, primary 62, the wire 60, to the contact-spring 44.

The method of ringing is given, although 100 it is not part of the present invention. By pressing the spring-contact 2 into engagement with the contact 4 the operator can then ring through the connecting cord and plug 9 and jack 13, and it will be seen that by pressing 105 the ringing-contacts, as shown, the operator can ring through any coil. It will further be seen that the operator cannot cut in his set without first ringing the bell 54 and then the bell 55. In cutting out the ringing of the 110 bells is reversed, thus indicating to subscribers that the line is free from listening or interruption by the operator. It is manifest that a third party cannot be connected with the two conversing parties by means of the 115 two switches 46 and 46^a, because when one switch is closed it cuts out the switches to the right of it.

Having thus described my invention, I claim as new and desire to secure by Letters 120 Patent—

1. In a telephone-circuit, a transmitter in the circuit at the central office, and a plurality of alarm-sounding devices of different tone or pitch, and arranged in the circuit adjacent 125 to the said transmitter, substantially as specified.

2. In a telephone-circuit, a transmitter in the circuit at the central office, two bells of different pitch arranged adjacent to the transmitter and in the circuit, and a switch operating to close the circuit through the bells one after the other, substantially as specified. 130

3. In a telephone-circuit, a transmitter in

- the circuit at the central office, bells of different pitch arranged adjacent to the said transmitter, the said bells being arranged in different circuits adapted for connection with the main telephone-line, and a switch mechanism operated in two directions to successively close the bell-circuits during both backward and forward movements of the switch, substantially as specified.
- 10 4. In a telephone-circuit, an alarm-transmitter arranged at central in the circuit, an operator's transmitter, and bells of different

pitch arranged forward of the alarm-transmitter, and means for successively closing the circuit through said bells, substantially as specified.

In testimony whereof I have signed my name to this specification in the presence of two subscribing witnesses.

WILLIAM EDWIN PEMBLETON.
